UNITED STATES PATENT OFFICE

CHAUNCEY D. ALLEN, OF PHILADELPHIA, PENNSYLVANIA, ASSIGNOR TO CONSOLIDATED ASHCROFT HANCOCK COMPANY, OF NEW YORK, N. Y., A CORPORATION OF DELAWARE

DESIGN FOR A VALVE

Application filed December 20, 1930. Serial No. 38,037. Term of patent 7 years.

To all whom it may concern:

Be it known that I CHAUNCEY D. ALLEN, a citizen of the United States of America, residing at Philadelphia, in the county of Philadelphia and Commonwealth of Pennsylvania, have invented a new, original, and ornamental Design for a Valve, of which the following is a specification, reference being had to the accompanying drawing, forming a part thereof.

In said drawing:

Fig. 1 is a front elevation of a valve showing my new design;

Fig. 2 is an end elevation thereof, and Figs. 3 and 4 are a top plan and a bottom view, respectively.

I claim:

The ornamental design for a valve substantially as shown.

Signed by me at Boston, in the county of Suffolk, and State of Massachusetts, this fourth day of December, 1930.

CHAUNCEY D. ALLEN.
